UNITED STATES PATENT OFFICE.

CHARLES JULES MÉGEVET AND LUCIEN PICKER, OF GENEVA, SWITZERLAND.

CARBURETER FOR INTERNAL-COMBUSTION ENGINES.

1,090,556.

Specification of Letters Patent. Patented Mar. 17, 1914.

Application filed February 8, 1912. Serial No. 676,223.

To all whom it may concern:

Be it known that we, CHARLES JULES MÉGEVET, manufacturer, and LUCIEN PICKER, engineer, both citizens of Switzerland, residing at Rue Malatrex 7 and 9, Geneva, in the Confederation of Switzerland, have invented certain new and useful Improvements in Carbureters for Internal-Combustion Engines, of which the following is a specification.

10 The present invention refers to carbureters for internal combustion engines of the type in which the liquid fuel is supplied to a spraying nozzle and air is passed over the nozzle, causing spraying of the fuel, to which 15 mixture of fuel and air a regulatable quantity of air is added before the same is admitted to the cylinder.

According to the present invention, the admission of the air is controlled by two 20 valves, the relative positions of which may at will be changed to modify the ratio of the sections of the passages for the mixture from the nozzle and the diluting air. The said valve may further be arranged so as to provide 25 for a regulation of the section of the passage for the mixture from the nozzle without changing the position of the valve controlling the admission of the diluting air so as to permit the adjustment of the carbureter for the working at full load of the 30 motor without any adjustment for the working with reduced load and vice-versa, as will hereinafter be more particularly described.

In the drawing, Figure 1 is a horizontal 35 section of our improved carbureter. Fig. 1^a is a partial detail plan view some parts being shown in section. Fig. 2 is a section along line A—B of Fig. 1. Fig. 3 is a section along line C—D of Fig. 2, and Fig. 4 is a diagrammatic view illustrating a modified form 40 of the inlet valves.

45 a is the spraying nozzle of usual type to which the liquid fuel is supplied from a tank b. The spraying nozzle a is placed in a channel c, the section of which is such that the fuel is drawn from the nozzle and the spraying of the same is produced by the air drawn through the channel; the carbureted gas entering the motor at the inlet d. The 50 channel through which the mixture passes through the apparatus, as shown in Fig. 1, is horizontally bent to form a C and the spraying nozzle is placed in the end of the channel and the carbureted gas is drawn into the motor at the other end thereof. By so 55 doing, the small drops or particles of liquid

fuel issuing from the nozzle are projected against the surface e where they are still further atomized. The bent form of that part of the channel further causes the mixture to whirl in flowing through the apparatus and thus a thorough mixture of the atomized fuel with the air is produced.

The quantity of gas mixture admitted to the motor is controlled by the cylindrical piston valve f, the free end of which may more or less obstruct the passage through which the mixture from the nozzle reaches the inlet opening d. In the said valve there is provided an inlet opening f¹ (see Fig. 1^a) 70 for additional air. The piston valve f is slidably mounted in a sleeve valve i, in which there is provided an opening i¹ for the passage of the air. The valve i carries a lug or protruding part i² provided with a screw k screwed in a corresponding lug l¹ of the casing l of the carbureter and connected to the valve f is a rod g on which is mounted a nut g¹. Surrounding the rod g is a spring h, one end of which contacts with the nut g¹ and the other end of which rests in a depression of a revoluble head m. This head m is seated on the free end of the sleeve i and is provided with a hub through which the rod g passes. A stud g² is fixed in the 80 rod g and extends into a longitudinal groove in the hub of the head m in which latter the stud may move longitudinally, thus providing for a longitudinal or axial movement of the cylindrical piston valve f, but causing 85 the same to be turned whenever the head m is turned on the sleeve i.

The different parts of the carbureter being in the positions shown in the drawing, the piston valve may be moved from left to 95 right, in Fig. 2, by compressing the spring h. This may be caused by the action of the governor of the motor on the rod g or any other device for causing the throttling of the gases, the free end of the piston f reduces 100 the area of the passage for the mixture from the nozzle, and at the same time the opening f¹ is shifted relatively to the opening i¹, and thus the passage for the admission of air is also reduced. In this manner, 105 the quantity of carbureted gas admitted to the motor is reduced but the composition of the mixture admitted to the cylinder during the operation at reduced load of the motor is not changed and thus a constant composition of the mixture for all loads is obtained. By turning the head m, the open-

ing f^1 may be shifted relatively to the opening i^1 and thus the area of the passage for the air may be adjusted, during the operation of the motor, without any change in the area of the passage for the mixture from the nozzle. Thus the proportion of mixture from the nozzle and the air, or the composition of the gas mixture supplied to the motor for the operation at reduced load may be regulated, and said composition having been adjusted remains constant for any position of the piston valve f because if said piston valve is actuated to cause throttling of the mixture from the nozzle, a corresponding reduction of the area of the opening for the admission of air is produced at the same time, as herein before explained. On the other hand, whenever the screw k is screwed or unscrewed, the sleeve i and the valve f are moved together without any change of their relative position. Thus no change is made in the area of the opening for the admission of air but the free end of the piston f being shifted relatively to the inlet opening d , the area of the passage for the mixture from the nozzle is changed and thus the proportions of the composition of the carbureted gas supplied to the motor for the operation at full load of the same may be adjusted.

We claim as our invention:

1. A carbureter comprising a casing having a passage therein leading from an air inlet to an inlet for an engine cylinder, a spraying nozzle in the said passage, a cylindrical valve, a sleeve valve placed concentrically on the cylindrical valve, the said valves being provided with apertures and being revolubly adjustable to regulate the available area of said apertures, and means for moving said valves together longitudinally to adjust the cylindrical valve to position to control the inlet to the said engine cylinder without changing the available area of said apertures.

2. In a carbureter and in combination, a casing having a passage therein leading from a free air inlet to an inlet for an en-

gine cylinder, a spraying nozzle in said passage, a sleeve valve having an air inlet therein, a revoluble head seated upon the end of said sleeve valve and provided with an in-turned hub having a longitudinal slot therein, a cylindrical valve slidably mounted within said sleeve valve and provided with an air inlet, a rod having one end connected to said cylindrical valve and passing through the hub on said head, a stud fixed on said rod and entering the longitudinal slot in said hub, a helical spring surrounding said rod, a nut upon the free end of said rod, one end of the said helical spring contacting with said nut, and its other end resting in a depression in the said head around its hub.

3. In a carbureter and in combination, a casing having a passage therein leading from the free air inlet to an inlet for an engine cylinder, and provided with a lug on one side, a spraying nozzle in said passage, a sleeve valve having an air inlet therein and provided with a lug corresponding with and in alinement with the said lug upon the casing, an adjusting screw connecting said lugs, a revoluble head seated upon the free end of said sleeve valve and provided with an in-turned hub having a longitudinal slot therein, a cylindrical valve slidably mounted within said sleeve valve and provided with an air inlet, a rod having one end connected to said cylindrical valve and passing through the hub on said head, a stud fixed on said rod and entering the longitudinal slot in said hub, a helical spring surrounding said rod, a nut upon the free end of said rod, one end of the said helical spring contacting with said nut and its other end resting in a depression in the said head around its hub.

In testimony whereof we have affixed our signatures in presence of two witnesses.

CHARLES JULES MÉGEVET.
LUCIEN PICKER.
